C. STEENSTRUP

ELASTIC FLUID TURBINE ROTOR AND METHOD OF MAKING SAME

Filed Feb. 16, 1920

Inventor:
Christian Steenstrup
by *Albert G. Davis*
His Attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

ELASTIC FLUID TURBINE ROTOR AND METHOD OF MAKING SAME.

Application filed February 16, 1920. Serial No. 359,078.

To all whom it may concern:

Be it known that I, CHRISTIAN STEENSTRUP, a citizen of the United States, residing at Schenectady, county of Schenectady, State of New York, have invented certain new and useful Improvements in Elastic Fluid Turbine Rotors and Methods of Making Same, of which the following is a specification.

10 The present invention relates to elastic fluid turbines and particularly to the rotors or rotor elements of such machines.

The primary object of my invention is to provide an improved rotor structure comprising a blade-carrying element or elements with blades fastened thereto, and an improved method of making such a structure.

15 A further object of my invention is to provide an improved form of bucket which can be advantageously manufactured at a low cost and which is particularly well adapted for use in carrying out my present invention.

20 In carrying out my present invention, I take a blade-carrying element which may be in the form of a wheel, a drum, a ring, or other desired form, and assemble all the blades thereon in the positions they are to 25 have in the completed rotor. In carrying out this assembling operation, the blades need be fastened in position in a temporary manner only and this may be accomplished for example, by suitable spacing and clamping

30 means which are removable or by suitable engaging parts between the blade-carrying element and the blades which are sufficiently strong to anchor the blades firmly in position for the time being. The assembled

35 structure is then placed in a suitable muffler and the blades and blade-carrying element permanently fastened together by the method as set forth in my co-pending application for Letters Patent Serial No. 354,014,

40 filed January 26, 1920, which method I term alloy-uniting or alloy-fastening. As there-

45 in set forth such method comprises generally bringing the surfaces of the parts to be joined into close, intimate contact so that

50 the intervening spaces are materially less than a mil in width, and in fact immeasurably small, and then while held in such

55 intimate contact, introducing alloying metal into the joint or joints to thereby form an alloy film binding said parts together.

Various alloying metals may be used in carrying out such method but preferably I employ copper, and carry the method out by heating the parts to a suitable temperature in the presence of a reducing atmosphere, preferably of hydrogen.

60 My present invention is applicable to rotors or rotor elements for various types of turbines. It is well adapted, for example, for use in building up the blade rings for 65 radial flow turbines, such as turbines of the Ljungstrom type, and for fastening buckets on the wheel of a Curtis turbine, and in the following specification I have particularly illustrated and described such applications 70 of my invention. It is to be understood, however, that my invention is not limited to these particular applications.

75 In the drawing, Figs. 1 to 13 inclusive illustrate my invention as utilized in building up a blade ring for a radial flow turbine. Figs. 1 and 2, Figs. 3 and 4, and Figs. 5 and 6 are side and edge views respectively of three types of rings which may be utilized as blade-carrying elements; Fig. 80 7 is a perspective view of a piece of bucket stock; Fig. 8 shows a bucket made from a piece of stock as shown in Fig. 7; Fig. 9 is an end view of a bucket as shown in Fig. 8; Fig. 10 shows the manner in which a 85 blade ring is assembled; Fig. 11 illustrates a completely assembled blade ring and the manner of alloy-uniting it; Fig. 12 shows a slight modification; Figs. 13 and 14 show an application of my invention to a turbine 90 wheel of the Curtis type; and Fig. 15 illustrates a modification.

95 In carrying out my invention, as illustrated in Figs. 1 to 11 inclusive, I first provide a number of suitable rings 20 which may be solid rings, as shown in Figs. 1 and 2 or rings made up from a plurality of layers or sheets alloy-united together as shown in Figs. 3 and 4 or Figs. 5 and 6. Preferably I employ the latter arrangement because of its greater strength and freedom from possible flaws. In Figs. 3 and 4 a ring 20 is shown as comprising a plurality of thin, flat disks 21 stacked upon each other and alloy-united together; in Figs. 5 105 and 6 a similar structure is shown except that the layers of material 22 are formed by spirally winding a ribbon or strip of thin material upon itself and alloy-uniting the whole together. A ring 20 after being 110

formed, particularly in the manner shown in Figs. 3 and 4 or Figs. 5 and 6, may then be ground down and finished by suitable machine operations to bring it to correct dimensions.

After rings 20 of the desired form are provided, I then assemble the blades 25 in correct relation to form a blade ring and fasten the whole together in a temporary manner, preparatory to alloy-uniting them after the manner set forth in my above referred to application for Letters Patent. Various arrangements of temporary fastening means may be utilized, the essential thing being that they bring the surfaces to be joined into close intimate contact and maintain them thus during the alloy-uniting process. One arrangement which I have found most advantageous comprises providing in the faces of rings 20 spaced openings or holes 26 and forming blades 25 having short projections 27 at their ends which are inserted into such holes. Such blades may be made by taking strips of blade stock as shown in Fig. 7 which stock may be made by drawing through suitable dies, cutting it into suitable blade lengths, and then upsetting the ends of the blade length to form the projections 27, at the same time forming also a fastening flange 28, thus providing an enlarged surface for seating against the surfaces of rings 20. An upsetting operation as just referred to is a comparatively simple matter and may be carried out in any suitable manner. As a result, blades of this type may be manufactured at a low cost. Projections 27 are of such size that they fit tightly holes 26 so that when the blade ring is assembled after the manner shown in Fig. 10, the blades will be firmly anchored in a temporary manner to the rings with the surfaces to be joined in close contact. The holes 26 are spaced apart so as to correctly position the blades on the rings.

After being assembled in the foregoing manner, the blade ring structure is then alloy-united in accordance with the method set forth in my co-pending patent application already referred to, thereby joining the entire blade ring structure into an integral whole. This alloy-uniting process is carried out by placing the blade ring structure in a muffler 29, Fig. 11, to which a reducing gas, as hydrogen, is admitted through a pipe 30 and discharged through a pipe 31. The blade ring structure may be placed on a light coating of sand or asbestos 32 on a supporting plate 33, the sand or asbestos being used in order to insure that the ring structure is equally supported at all points of its surface. This is done by pressing the ring down firmly on the sand or asbestos which will cause the latter to yield slightly and shift around so as to come into engagement with all parts of the adjacent ring

structure surface. On top of the structure a weight 34 may be placed for the purpose of applying pressure to the structure. Or instead of weight 34 some other means, such as a clamping means, may be provided for the same purpose. Between weight 34 and the top of the structure I preferably provide a light coating of asbestos or sand as indicated at 35, for the same purpose as pointed out in connection with coating 32. The blade ring structure is then heated to a temperature of about 1140° C. to 1150° C. in this reducing atmosphere, a suitable amount of copper or other alloying material being provided at desired points. For this latter purpose some small copper wires as indicated at 36 (Fig. 10) may be put around the structure, or a small bit of copper may be placed in the bottom of each hole 26 as indicated at 37, it being only necessary in any event that a small amount of the alloying metal be provided in the vicinity of the surfaces to be joined. After the structure has been thus joined into one complete whole it is removed from the muffler 29 and finished and arranged as found desirable for use in the turbine structure for which it is intended.

A blade ring as just described when used in a turbine of the Ljungstrom type is supported at one end by an expansion ring, the other end being free and for this reason it is necessary that such blade rings be very rigid, particularly in a transverse direction. Heretofore, so far as I am aware, such blade rings have been made by a welding process which has been expensive and required a large amount of time. By my improved method I find that I can make a blade ring of greater strength than those made by previous known methods in a very much shorter time and at a small fraction of the cost in both labor and material. This will be better appreciated when it is considered that by previous known methods, the blades have been welded one at a time first to one blade ring, and then to the other and as there are quite a number of concentric blade rings used in a turbine of this type and some of them quite long, the building up of these blade rings for a complete rotor has been a long and expensive piece of work attended with considerable difficulty. By my improved method all the blade rings for a complete rotor may be quickly and readily assembled in the initial, temporary manner by relatively unskilled help and all the blade rings for a complete rotor may then be placed in the muffler in nested relation to each other and alloy-united at the same time. This makes it possible to do in a single day, work which formerly has required a very much longer time.

In Fig. 12 I have shown a modified ar-

angement for initially fastening together the rings and blades. In this arrangement the blades 40 have flat ends in which are located holes 41 and in rings 42 are holes 43. The buckets are then fastened to the rings by pins 44 which are fitted into such holes.

Referring now to Figs. 13 and 14, 45 indicates the web and 46 the rim of a turbine 10 wheel of the Curtis type. In rim 46 are spaced holes 47 in which are located short pins 48 on the inner ends of buckets 49. This forms an initial means for fastening the buckets to the wheel rim and bringing 15 the engaging surfaces into close contact, at the same time properly spacing the buckets. As will be seen from Fig. 14, the bottoms of the buckets are curved by the necessary amount to cause them to follow the contour 20 of the wheel rim. After the buckets are initially fastened on the wheel rim, a bucket cover 50 is initially fastened in position by any suitable means such as for example by means of tenons 51. The bucket cover may 25 be made in sections or it may be one continuous piece. The wheel structure as now assembled is then alloy-united, in the manner already referred to thereby permanently uniting the buckets to the wheel rim and 30 the bucket cover to the buckets.

In Fig. 15 I have shown a modification particularly intended for building up blade rings for use with radial flow machines and well adapted for large blade rings. In this 35 arrangement the buckets 55 which may be similar to the buckets shown in Figs. 8 and 9 are attached to rings 56 by the method already described. Rings 56 may be relatively thin and may be originally plain 40 rings which are afterwards finished to provide the undercut tongues 57. The rings of individual blades thus formed may then be built up into a complete blade ring, as shown, for example, in Fig. 11 by joining 45 them together by means of strengthening rings 58 which have grooves in which tongues 57 are located. Such joint may be made by rolling the sides of the grooves into engagement with tongues 57.

50 What I claim as new and desire to secure by Letters Patent of the United States, is:

1. A blade ring comprising a plurality of spaced annular rings and blades located between them and united thereto by a metal having a lower melting point than that of the rings and blades, said rings and blades having engaging parts which serve initially to hold the blade ring as a whole assembled.

60 2. A blade ring comprising a plurality of spaced annular rings and blades located between them and united thereto by a metal having a lower melting point than that of the rings and blades, the adjacent faces of said rings being provided with holes and the

blades being provided with projections which are located in said holes.

3. A blade ring comprising a plurality of spaced rings and blades located between them and alloy-united thereto, one or more 70 of said spaced rings comprising a plurality of discs of thin material alloy-united together.

4. In an elastic fluid turbine, a blade ring comprising a plurality of rings in spaced 75 relation to each other, each ring being made up of a number of thicknesses of metal alloy-united together, the adjacent faces of said rings having circumferentially spaced holes therein, and blades located between said 80 rings and alloy-united thereto, said blades being provided with projections which fit into said holes, whereby the blades may be fastened into position on the rings prior to their being alloy-united thereto. 85

5. In an elastic fluid turbine, a blade carrying element and a blade united thereto by a metal having a lower melting point than that of the element and blade, said blade having a flanged end which presents 90 an enlarged surface for engagement with the element.

6. In an elastic fluid turbine, a blade carrying element, blades united thereto by a metal having a lower melting point than 95 that of the element and blades, said blades having flanged ends which present enlarged surfaces for engagement with the element, and means for initially positioning the blades on said blade carrying element. 100

7. In an elastic fluid turbine, a blade carrying element having spaced holes, and blades having projections which fit into said holes and flanged ends which present enlarged surfaces for engagement with the element, said blades being united to the element by a metal having a lower melting point than that of the element and blade. 105

8. A turbine blade comprising a strip of blade material having a flange at at least 110 one end which provides with the end of the blade an enlarged fastening surface.

9. A turbine blade comprising a strip of blade material having a flange at at least one end which provides with the end of the 115 blade an enlarged fastening surface, and an attaching projection on said end.

10. The method of making a turbine blade for alloy-uniting to a blade-carrying element, which comprises taking a length of 120 blading material and upsetting at least one end of it to form an enlarged flat end surface.

11. The method of making a turbine blade for alloy-uniting to a blade-carrying element, which comprises taking a length of 125 blading material and upsetting at least one end of it to form an enlarged flat end surface with a short projection extending therefrom. 130

12. The method of making a blade ring which comprises assembling a plurality of rings and blades in correct relation to each other to form a complete blade ring structure, temporarily fastening them together, and then permanently fastening them together by alloy-uniting them by means of a metal having a melting point lower than that of the rings and blades.
- 10 13. The method of making a blade ring comprising a plurality of parallel reinforce-
- ing rings with blade lengths between them which comprises building up the complete blade ring structure, temporarily fastening it together, and then permanently uniting the built up structure by means of an alloying metal having a melting point lower than that of the rings and blades. 15

In witness whereof, I have hereunto set my hand this 13th day of February, 1920.

CHRISTIAN STEENSTRUP.
